[57] CLAIM

The ornamental design for an electric kneader, as
shown and described.

DESCRIPTION

FIG. 1 is a front elevational view of an electric kneader, showing my new design;
FIG. 2 is a rear elevational view thereof;
FIG. 3 is a top plan view thereof;
FIG. 4 is a bottom plan view thereof;
FIG. 5 is a right side elevational view thereof;
FIG. 6 is a left side elevational view thereof;
FIG. 7 is a cross-sectional view thereof, taken along line
7—7 of FIG. 6; and,
FIG. 8 is a perspective view thereof.
